UNITED STATES PATENT OFFICE

119,878

DESIGN FOR A GLIDER OR SIMILAR ARTICLE

Jacob C. Feldman, Boston, Mass., assignor to
New England Bedding Company, Medford,
Mass., a corporation of Massachusetts

Application October 26, 1939, Serial No. 87,874

Term of patent 14 years

To all whom it may concern:

Be it known that I, Jacob C. Feldman, a citizen of the United States of America, residing at Boston, in the county of Suffolk and Commonwealth of Massachusetts, have invented a new, original, and ornamental Design for a Glider or Similar Article, of which the following is a specification, reference being had to the accompanying drawing, forming a part thereof.

Fig. 1 is a perspective view of the glider, showing my new design;

Figs. 2 and 3 are top plan and end elevational views, respectively, of the glider; and
Fig. 4 is a front elevational view of one end of the glider.

The dominant features of my design reside in the portions shown in solid lines.

I claim:

The ornamental design for a glider or similar article, substantially as shown and described.

JACOB C. FELDMAN,
